UNITED STATES PATENT OFFICE.

HERBERT BARNETT, OF KANSAS CITY, MISSOURI.

OIL-CAN.

1,331,409.

Specification of Letters Patent. Patented Feb. 17, 1920.

Application filed November 17, 1917. Serial No. 202,670.

To all whom it may concern:

Be it known that I, HERBERT BARNETT, a subject of the King of Great Britain, residing at Kansas City, in the county of Jackson and State of Missouri, have invented 5 new and useful Improvements in Oil-Cans, of which the following is a specification.

This invention comprehends improvements in metallic oil cans.

10 The primary object of the invention resides in the production of a can of the above stated character which is simple in construction, durable and efficient in use, and one wherein provision is made of a body 15 for the can so designed to enable the operator to firmly grasp the bottom of the can when it becomes necessary to lift or tilt the can when in a filled condition; as heretofore the necessary gripping action on the 20 can without the liability of such slipping or dropping from the hand of the operator, more especially in view of the nature of the contents of the can, could not be successfully obtained.

25 With the above and other objects in view, the invention consists in the novel features, details of construction and combination of parts which will hereinafter be more fully set forth, illustrated in the accompanying 30 drawing and pointed out in the appended claim.

In the drawings:

Figure 1 is a perspective view of an oil can illustrating the same in a tilted position 35 by the operator;

Fig. 2 is a vertical sectional view; and Fig. 3 is a bottom plan view.

Referring more particularly to the accompanying drawing, the preferred embodiment of the invention illustrated in the accompanying drawing is that of an oil can comprising a cylindrical body portion 5, a filling opening 6 provided centrally in the inverted conical-shaped top 7, and the bail 40 8 is pivotally mounted in the ears 9 adapted to be grasped by one hand of the operator when the can is either being conveyed or tilted.

The chief characteristic of this invention 50 is the provision of a novel form of bottom 10 so designed to adapt the contents contained in the can body 5 to be poured therefrom through the spout 11 without any liability of the can slipping or dropping from 55 the other hand of the operator, as clearly

shown in Fig. 1 of the drawing. To this end, the bottom 10, on an axial horizontal line is stamped or depressed inwardly to provide within the can body a substantially U-shaped hand grip 12, and so designed to 60 facilitate a firm grasp of the hand within the recess 13 thereof. In other words, the hand grip 12 by being struck inwardly of the bottom 10, permits the bottom 10 of the can, upon the transportation or storage thereof, 65 to sit in a flat condition, preventing any liability of the capsizing of the can and further of the mutilation of the hand grip, and in order to afford sufficient capacity within the recess, the grip 12 has one of its walls 14, 70 bent upon the inner surface of the bottom 10, the opposite wall 15 of the recess connected with the wall 14 through the medium of the curved connecting wall 16, being bent in a downward and outward inclined direction 75 from the wall 14, to provide the flared outer end 17 of the recess opening out through the bottom 10 of the can. By this construction, it is manifest that when the tip ends of the fingers of the operator are 80 inserted in the contracted inner end 18 thereof, the flared outer end 17 of the recess accommodates sufficient capacity for the hand, because as is obvious it is necessary for the operator to close his hand when desiring to 85 obtain the necessary gripping action in the hand grip 12, when the can is to be lifted or preferably tilted. Aside from the heretofore referred to point of location of forming the recess with respect to the bottom 90 10, the former is further provided in axial vertical alinement with the point of pivotal connection of the bail 9 with the can, consequently assuming the can is of a five gallon capacity or more, will permit the contents 95 to be easily poured through the spout 11 thereof.

From the foregoing description, taken in connection with the accompanying drawing, the advantages of construction and the 100 method of operation will be readily apparent to those skilled in the art to which the invention relates, and while I have described the principles of operation of the invention together with the device which I now consider to be the best embodiment thereof, I desire to have it understood that the device shown is merely illustrative and that such changes may be made when desired as are 105 within the scope of the appended claim. 110

Having thus described the invention, what is claimed as new is:—

A metallic oil can comprising a cylindrical body portion provided with a closed bottom wall stamped at a point through the horizontal center thereof to provide within the can bottom a substantially U-shaped finger grip, the walls forming the finger grip being

so bent to provide therein a recess having a contracted inner end and a flared outer ¹⁰ end, a bail pivotally connected to said can at a point in vertical alinement with the point of formation of the hand grip, substantially as and for the purpose set forth.

In testimony whereof I affix my signature. 15
HERBERT BARNETT.
